UNITED STATES PATENT OFFICE

99,157

DESIGN FOR AN ETHERIC VIBRATOR CABINET

Hiel Eugene Crum and Anna May Crum,
Indianapolis, Ind.

Application January 27, 1936, Serial No. 60,841

Term of patent 14 years

To all whom it may concern:

Be it known that Hiel Eugene Crum and Anna May Crum, both citizens of the United States, residing at Indianapolis, in the county of Marion and State of Indiana, have invented a certain new, original, and ornamental Design for an Etheric Vibrator Cabinet, of which the following is a specification, reference being had to the accompanying drawing, forming a part thereof.

Fig. 1 of the drawing is a front perspective view of the cabinet and Fig. 2 is an end elevation of the same, showing our new design.

The other end of the cabinet or box is sub-

stantially like the end shown in the drawing, and the back side is substantially like the front side at top, bottom and two end corners. Otherwise the back side is a plain flat surface except the cord and its attachment, substantially at the middle of that side near the bottom.

We claim:

The ornamental design for an etheric vibrator cabinet, substantially as shown and described.

In testimony whereof we affix our signatures

HIEL EUGENE CRUM.
ANNA MAY CRUM.
